UNITED STATES PATENT OFFICE.

JAMES DWIGHT McCANN, OF FALLS CITY, NEBRASKA.

MEASURE FOR DRAFTING GARMENTS.

SPECIFICATION forming part of Letters Patent No. 334,457, dated January 19, 1886.

Application filed January 28, 1885. Serial No. 154,231. (No model.)

To all whom it may concern:

Be it known that I, JAMES D. McCANN, of Falls City, in the county of Richardson and State of Nebraska, have invented a set of Improved Measures for Drafting, Designing, and Cutting Out Garments, of which the following is a specification.

The invention consists in a set of instruments for the drafting of garments, furs, gloves, and mittens, as hereinafter described.

My instruments embody a new, useful, and improved method of measuring, drafting, or designing. They consist of a series of geometrically-scaled chest or bust measures, an angle-measure, and a former or scaled curve, to be used in the drafting and construction of scaled diagrams. They serve as guides from which any and all kinds of full-sized garments or wearing-apparel may be drafted, designed, cut, and made.

By my invention a consecutive set of scaled sizes may be drafted and cut, ranging from the small chest or bust measure (marked sixteen) to that of forty-seven inches, thus making thirty-two or more sizes which may be drafted or cut from the same diagram with the same mathematical exactness and with the same instruments.

Figure 1 is a plan view of the chest-scale. Fig. 2 is a similar view of the angle-scale, with the chest-scale pivoted at the vertex of its angle. Fig. 3 is a plan view, to show the joint in angle-measure, whereby the short arm may be folded down on the long one. Fig. 4 is a plan view of the curve-scale. Fig. 5 is a diagram illustrative of a garment as it is cut out.

The following measurements are to be taken moderately tight, and preferably over some tight-fitting garment: First, girth of the neck; second, girth of the arm close to the shoulder-joint; third, girth of chest or bust close up underneath the arms; fourth, from the top of the spinal column down the back sharp onto the line ranging with the upper point of the hips; fifth, girth of waist close down onto the upper point of the hips; sixth, girth around over the largest part of the hips; seventh, length of arm from upper point of the shoulder round over the elbow to the wrist, marking figures at elbow and wrist. (arm to be held in an easy bent position;) eighth, girth of sleeve at elbow and

at the wrist; ninth, the distance across the back between the outer circles of the armholes; tenth, the distance from the under side seam 55 beneath the arm to the center of the chest or bust in front.

In using my scale and diagrams the following measurements are only necessary: First, the chest or bust measurement around the body close up underneath the arms determines the chest, bust, or scale to be used; second, the distance from the top of the spinal column down the back to the waist determines the length of the waist; third, girth of the waist 60 down close onto the top of the hips; fourth, length of sleeve from the upper point of the shoulder around over the elbow to the wrist; fifth, girth of sleeve at elbow and wrist; sixth, the distance across the back between the outer 70 circles of the armholes; seventh, the distance from the side seam beneath the arm to the center of the chest or bust in front.

The above seven measurements will give all the data necessary to make any changes required in the drafting of the body of any garment, or the body of any and all wearing-apparel.

In the application of my method of drafting, designing, or making of diagrams for wearing-apparel there are three essential instruments required, which are of the following construction and dimensions:

In Figure 1 of the drawings, A represents the chest or bust measure or scale, which runs 85 or ranges in consecutive numbers, from sixteen inches to that of forty-seven inches, representing the number of inches around the chest or bust of a person.

The chest-measure is made in the following 90 gradation of scales: The chest measure or scale number 30 is taken as the base or dividing line between the man and the youth, maid or miss, and is the true English standard inch and foot measure, and all prepared diagrams are preferably scaled upon this base or dividing line. The twelve inches of the foot are called "spaces," which are subdivided into ten equal parts or tenths.

The chest-measurements of persons generally 100 vary from about thirty to forty-seven inches; hence it is most convenient to have about eighteen straight measures like that shown in Fig. 1 of the drawings.

The above-said chest measures or scales may be made of wood, flexible tape, steel, vulcanized rubber, or any other material which will answer the purpose for which they are used. 5 The design of their width is three-fourths of an inch, and the scales printed upon the same will determine their length.

In Fig. 2 of the drawings, B represents the angle measure. The long arm *b* of said angle 10 is one and one-fourth inch wide by twenty inches long. The short arm *b'* of the same is one inch wide by twelve inches long. The thickness of said angle is from one eighth to one-fourth of an inch. Both sides of the arms are 15 spaced off into one-inch spaces upon the outer margin, and the inch-spaces to be subdivided into ten equal spaces, the spacing to be made both ways from the vertex of the angle, the two arms being connected by a circular 20 hinge, *B'*, which enables the short arm of the angle to be folded down evenly upon the long arm. A spring-catch, *c*, will rest against the edge of the inner or outer circle of the hinge, which is scaled and properly notched, so that 25 the short arm of the angle may be fixed at any given angle to the long arm.

In Fig. 3 is a view of the hinge at the junction of the arms of the angle-measure, the upper and outer plate of hinge being cut away 30 at the circle shown. A piece is made to fit the same, neatly notched and scaled upon one-half of the edge of the same. The said piece is then riveted upon the proper side of the tongue of the short angle of said square, so 35 that it will nicely fit up into the cut-away circle, and a screw is placed in the center at *a* to fasten the parts of hinge together. When the short arm *b'* is moved to or from the long arm *b*, the notched and scaled circle *d* turns 40 around in the cut-away circle on the long arm *b*. Near the edge of the cut-away circle is a small catch-spring, *e*, which catches in the notches of circle *d* and firmly fastens the same at any given angle. Catch-spring *f* is 45 fastened at *e* at the junction of arms *b* *b'*, with the screw *g* to receive and hold in place scale A. Two more like springs are used to catch and hold scale A, one being placed in each 50 arm of the angle-measure at a suitable distance, so as to hold said scale.

In Fig. 4 of the drawings C represents the curved scale, which is so constructed in curves and circles that when used in conjunction with the chest and angle measure the true 55 circles and natural curves required to secure a perfectly-fitting garment may be easily and readily obtained. The curve-scale is a fraction over twenty-three inches long and one-eighth of an inch in thickness, the large end 60 having a maximum width of about five inches, and the small one a width of about three and three-eighths of an inch. Said curved scale may be made of wood, vulcanized rubber, or any other suitable material. The outer margin (necessary to be used) of said former is 65 scaled or divided into one-inch spaces, and said one-inch spaces are subdivided into ten

equal parts, being the tenth part of an inch of the English standard measurement, but may be spaced or scaled in any other known or devised manner. A set of letters is placed upon both sides of said curved scale, two inches apart. The purpose of these letters is to determine what side, special, or particular part of the edge of said curved scale is to be used 70 in drafting the article of wearing-apparel. As a guide, and to guard against any possible mistake, the same class of letters as used upon said curved scale is also placed upon the diagrams, so that the user or drafter has only to 75 observe the letters upon the diagram and former and their relative positions, so as to determine the side and particular part of the edge of the former which is to be used. The said curved scale is made in two pieces jointed together in the narrowest place for the convenience of storage and carriage. It is easily 80 and quickly jointed together and also unjointed.

In Fig. 5 of the drawings is a sample diagram. In order to draft it I proceed as follows:

First. Place the angle-measure upon the paper or material upon which the diagram is to be drafted, with the outer edge of the long arm even with the edge of material next to you, and the short arm away from you, so as to rest upon the paper or goods. Draw a line along the outer edge of both arms of the angle-measure. The line along the long arm is 90 the vertical line and that of the short arm the parallel line. At a right angle to the vertical line and all other guide-lines must be drawn two parallel base-lines, from which all measurements are to be taken.

Second. Select chest measure or scale 30 and place the same in the catch-springs on the long arm of the angle-measure, with the end on which space one is marked at the vertex of the angles and even with the long arm *b*. 95 With the square even with the before-said marked lines, proceed to mark the required spaces down the vertical line as follows: Make a mark at the spaces designated. Space $1\frac{1}{2}$ determines the upper shoulder-line. Space $2\frac{1}{2}$ 100 determines the outer curve or circle of the neck. Space $3\frac{1}{2}$ determines the lower point of neck-curve. The above three spaces given 105 are all determined by the girth of the neck. Measure down $6\frac{3}{10}$ spaces, which is opposite the outer front curve of the arm-circle. Mark down 9 spaces, which is the chest or bust line passing close underneath the arms. The last two spaces are governed by the girth 110 of the arm close to the shoulder. Mark $9\frac{1}{2}$ 115 spaces, which determines the top of the under arm-seam. Mark down $12\frac{8}{10}$ spaces, which determines the upper point of the front side dart. Mark space $15\frac{1}{2}$, which gives waist-line as per measurement down the back. Mark $19\frac{1}{2}$, 120 which is determined by measurement over the hips. Mark $27\frac{1}{2}$, which gives full length of back part of skirt. Mark 28, which gives the 125 lower point of the front of the skirt. Move the 130

chest measure or scale from the long arm onto the short arm of the angle-measure. Fasten the scale in the catch-springs upon the said angle. Mark out on the upper base-line $3\frac{9}{10}$ spaces. Move down to marked space $1\frac{1}{2}$, keeping the long angle of the square always even with the vertical line. Mark out $9\frac{8}{10}$ spaces to point of shoulder-line, drawing a guide-line back to the vertical or base line, as 5 must be done with all guide-lines. Move to $2\frac{1}{2}$. Mark out three spaces. This gives the outer circle of the neck. Move down to $6\frac{3}{10}$. Mark out $8\frac{3}{10}$. Move down to 9. Mark out $10\frac{8}{10}$ spaces. This is the chest or bust measure or scale-line. Move down to $9\frac{1}{2}$. Mark 10 spaces, which gives the top of the under arm side seam. Move down to $12\frac{8}{10}$. Mark out $\frac{2}{10}$ and $5\frac{8}{10}$, which gives the curve of the front edge and top of the front side 15 dart. Move to $15\frac{1}{2}$. Mark out $\frac{3}{10}$, $4\frac{9}{10}$, $7\frac{3}{10}$, and 11, which gives waist-line front and side dart curves. Move to $19\frac{1}{2}$. Mark out $\frac{3}{10}$, $5\frac{1}{10}$, $7\frac{3}{10}$, and 12 spaces, giving front and front side dart curves and curve of swell over the hip. 20 Move down to $27\frac{1}{2}$. Mark out $13\frac{2}{10}$ spaces as width of skirt. Move to 28. Mark out $5\frac{6}{10}$ and 7 spaces, which gives the lower curve of front side dart lower circle of skirt. To complete the draft, take former or sealed curve and 25 obtain the required circles and curves (as per diagram) by noticing the given letters on the diagram and upon the former, which will designate the proper side and part of the said former to use.

The foregoing is the draft of one side of the front of a lady's walking-jacket. Where two pieces of the same dimensions are required, the goods are doubled and both pieces are cut at once. The necessary seam - cloth is allowed in the construction of all diagrams. 35

An indefinite number and variety of diagrams may be constructed from which any and all kinds of wearing-apparel may be drafted and cut upon the same principle by following the directions accompanying each 40 one. 45

One or more dashes placed parallel with any given line on the diagrams denote straight lines drawn with the straight-edge.

Stars placed upon the margin of separate 50 pieces or parts of the drafted diagrams determine the edges that are to be joined together in making up the garment.

Having thus described all that is necessary to a full understanding of my invention, what 55 I consider to be new, and desire to protect by Letters Patent, is—

A tailor's measure, C, reversely curved at its opposite ends, marked and notated with a figure for every inch-space near its margin, 60 having a letter over every other figure, and having more or less of the inch-spaces subdivided into tenths, as and for the purpose described.

JAMES DWIGHT McCANN.
